CONTROL FOR AIR SPRING PRESSURES IN
FREE-PISTON UNITSKenneth C. Cooper, Portland, Conn., assignor
to United Aircraft Corporation, East Hartford,
Conn., a corporation of Delaware

Application August 23, 1944, Serial No. 550,876

2 Claims. (Cl. 230—56)

1

This invention relates to a control for the air springs of a free-piston unit.

When a free-piston engine-and-compressor unit is subjected to changes in operating conditions such as compressor inlet or discharge pressures, or engine exhaust pressure, or the quantity of fuel injected, the length and position of the piston stroke may vary beyond the limits of satisfactory operation. Such changes may be compensated for by adjusting one or more of the controllable operating characteristics. A feature of this invention is the automatic control of the pressure in the air springs.

The copending application of Kalitinsky, Serial No. 550,883, filed August 23, 1944, issued on May 13, 1947, as Patent No. 2,420,483 discloses a stroke indicator adapted for adjusting one or more of the operating characteristics of the unit to maintain the desired piston stroke. The invention is directed to the structure by which the air spring pressure may be controlled in response to changes in piston stroke.

A feature of the invention is a compression control for the gas in the air spring which will adjust the pressure in the air springs as a function of the engine exhaust pressure to compensate for varying loads on the compressor. Another feature is a compression control which is actuated in response both to changes in piston stroke and to changes in exhaust pressure.

Other objects and advantages will be apparent from the specification and claims, and from the accompanying drawings which illustrate an embodiment of the invention.

Fig. 1 is a sectional view through the unit.

Fig. 2 is a fragmentary sectional view of the restraining linkage.

Fig. 3 is a diagrammatic view of the compression control and the stroke control.

The unit shown includes an engine cylinder 10 having reciprocating pistons 12 and 14 to which compressor pistons 16 and 18 in cylinders 20 and 22 are integrally connected. Sleeves 24 and 28 attached to the compressor pistons complete the reciprocating piston assemblies. The sleeves in combination with stationary pistons 26 and 30 over which they reciprocate form air spring cylinders.

The piston assemblies are moved apart by the burning of fuel injected into engine cylinder 10 through one or more nozzles 32. Air compressed in the air spring cylinders on the power stroke returns the piston assemblies. The assemblies are always maintained at equal distances from the center of the engine cylinder by a linkage,

which includes racks 34 and 36, Fig. 2, extending from pistons 16 and 18 and engaging a pinion 38 on a shaft 40.

Intake manifold 42, which extends around the engine and compressor cylinders, conducts air to intake valves 44 in the heads of the compressor cylinders through which air alternately enters opposite ends of the compressor cylinders. The compressed air leaves the cylinders through discharge valves 46, also at opposite ends of the compressor cylinders and passes into a central scavenging chamber 48 and end chambers 50 and 52. These chambers may be interconnected by a scavenging manifold, not shown.

Compressed gas from the scavenging chambers enters engine ports 54 and 56 which are uncovered by pistons 12 and 14 at the end of the power stroke, thereby permitting air to be blown through the engine cylinder. Gas in the engine cylinder is discharged through exhaust ports 58 into exhaust manifold 60.

The position of the piston at the inner end of its stroke is indicated by a master control 62 actuated by a cam 64 mounted on the shaft 40 as shown in Fig. 3. Since the pinion 38 is oscillated directly from the pistons, the movement of cam 64 is directly proportional to the piston stroke.

Fluid under pressure from a constant pressure source enters a passage 66 in a casing 68 through a conduit 70. This passage intersects a bore 72 adjacent the outer end and a throttling screw 74 controls the rate of flow into bore 72. A branch passage 76 from passage 66 connects with a port 78 in bore 72. A plunger 80 in bore 72 has a groove 82 which connects a port 84 alternately with port 78 or with a port 86. Port 84 is connected by a passage 88 to the inner end of bore 72. Port 86 is connected by a channel 90 in casing 68 and in an adjacent casing 92 to the inner (left hand) end of a bore 94 in casing 92.

A piston 96 in bore 94 is moved to the right by a calibrated spring 98. A plunger 100 extends through the piston and carries at its outer end a push rod 104. This rod has a roller 105 which is held against cam 64 by a spring 106. Plunger 100 has a central passage 108 connecting with spaced grooves 110 and 112 in the plunger by means of parts 113 and 115 respectively. Groove 112 aligns with openings 114 in a sleeve 116 carried by piston 96, and groove 110 is adapted to be uncovered by the end of sleeve 116 as the plunger is moved to the right by the cam as the pistons approach the inner ends of their stroke.

Fluid under pressure from the right hand end

of bore 72 enters the outer end of bore 94 through a connecting channel 118 moving piston 96 against the action of spring 98. As plunger 100 is moved to the right by cam 64 groove 110 is uncovered by sleeve 116 to permit discharge of fluid from the outer end of bore 94. The pressure in the outer end of bore 94 thus varies in accordance with the compression of spring 98 and as the piston stroke becomes shorter the piston 96 moves inward (to the left) increasing the spring tension and increasing the pressure at the right-hand end of bore 94 such that the change in pressure is proportional to the change in the end position of the stroke.

Since the right-hand end of bore 72 is connected directly to the end of bore 94, the change in pressure on the outer (right hand) end of the plunger 80 is also proportional to the change in the position of the piston stroke. The pressure on the opposite end of the plunger 80, which balances the pressure on the outer end, must vary in the same manner and is accomplished by the above-described porting in bore 72. In this way the pressure in the discharge conduit 120 is proportional to the spacing of the actual end of the piston stroke from the extreme inner position of the piston and changes in pressure in this conduit will be proportional to changes in the end position of the piston stroke. This pressure (and change in pressure) may indicate on a gauge 122 the exact position of the end of the piston stroke and may be used for actuating the compression control device for the air springs.

The outer end of plunger 100 may reciprocate in a chamber 124 which may be connected by a conduit 128 to the conduit 130 from the inner end of bore 94. Conduit 128 may be connected to a sump, not shown. Throttling screw 74 in passage 66 permits adjustment of the sensitivity of the control. A bellows 132 connected to passage 118 reduces pressure surges in the device.

The compression control includes a casing 138 having a bore 140 in which a plunger 142 is mounted. A port 144 is connected by a conduit 146 to a source of gas under pressure and an outlet port 148 is connected by a conduit 150 to the air spring. Plunger 142 is moved to the right by a spring 152, the tension of which is adjusted by a nut 154. A piston 156 in a bore 158 in a cap 159 on casing 138 engages a projecting pin 160 on the plunger. Fluid under pressure from the inner master control enters the end of bore 158 from conduit 120 to move plunger 142 against the action of spring 152. Piston 156 may have a small vent 162 and the inner end of bore 158 may be vented by a conduit 164 connecting with a sump.

If the fluid pressure from the master control increases, indicating that the inner end position of the piston stroke is moving away from inner dead center, plunger 142 is moved to the left so that a groove 166 in plunger 142 connects inlet port 144 and outlet port 148 to admit gas to the air springs for increasing the pressure in the air springs and thus moving the stroke inward again. If the fluid pressure from the master control decreases, spring 152 moves plunger 142 beyond the position shown to close port 144 and connect port 148 to a vent 167 for reducing the air spring pressure.

In operation fluid under pressure enters the master control past the throttle valve 74, through the right-hand end of bore 72 and into the right-hand end of bore 94 building up pressure in bore 94 until the piston 96 is moved far enough to the left to uncover groove 110. At this time the

pressure at the right of piston 96 will correspond to the spring force acting on the piston and will be indicated on the indicator 22 since the pressure at the right-hand end of bore 72 is maintained the same as the pressure at the left-hand end by reason of the control effected by plunger 80 as it moves relative to the inlet port 78. Since the plunger 100 is reciprocated in unison with the piston assembly of the free-piston unit through the medium of cam 64, its position within bore 94 is indicative of the position of the engine piston within the engine cylinder. The extreme right-hand position of plunger 100 would correspond to the extreme inner end position of the engine piston.

With the free-piston unit stopped, the pressure indicated on gauge 122 will be the pressure required to compress the spring 98 enough to permit piston 96 to uncover the groove 110. Thus, as the spacing of the piston assembly of the unit from its extreme end position increases, the pressure indication will also increase and the pressure in duct 120 will similarly increase.

When the free-piston unit is operating, the plunger 100 is reciprocated within the piston 96 in unison with the reciprocation of the piston assembly of the free-piston unit and the piston 96 is moved to the left by the pressure fluid acting upon it until the plunger 100 barely uncovers the groove 110 on each stroke. Thus, the piston 96 seeks a position, the spacing of which, from its extreme right-hand end position, is proportional to the spacing of the actual inner end of the piston stroke from its extreme inner end position.

As the stroke of the piston assembly shortens, thereby causing the actual inner end of the piston stroke to move away from the extreme inner end position, the pressure increases in duct 120 as determined by the spring 98 and operates on piston 156 to move the valve 142 to the left against the effect of spring 152 to admit compressed gas from the port 144 into the duct 150 and thence to the air spring, thereby increasing the gas pressure within the air spring for increasing the length of the piston stroke to restore the unit to its normal operation. If the stroke of the piston assembly of the free-piston unit lengthens or if the inner ends of the piston strokes begin to move more and more toward extreme inner end position, the pressure drops in the duct 120 and permits the valve 142 to move to the right under the influence of spring 152 to vent the air spring through the port 167.

In addition to controlling the air spring pressure from the inner master control, this pressure may also be dependent upon the engine exhaust pressure. To accomplish this, the exhaust duct 60 is connected by a conduit 168 to the end of casing 138 opposite to the piston 156. In this way when the exhaust pressure is low, the pressure from the inner master control acts only against spring 152. As the exhaust pressure increases, however, this pressure assists spring 152 and a greater pressure from the inner master control is necessary to move plunger 142 to establish gas connection between ports 144 and 148.

If the exhaust pressure of the unit increases, the compression pressure at the inner end of the stroke will also increase if the piston stroke remained the same. It may be desirable to maintain a constant compression pressure at the inner end of the piston stroke and to do this, the inner end of the piston stroke must move away from the center of the engine as the exhaust pressure increases. By loading plunger 142 with exhaust

5 pressure to resist the action of the pressure from the inner master control, it is possible either to maintain a constant compression pressure or to adjust the compression pressure as a function of the exhaust pressure.

It is to be understood that the invention is not limited to the specific embodiment herein illustrated, and described, but may be used in other ways without departure from its spirit as defined by the following claims.

I claim:

1. A free-piston unit having an engine cylinder, opposed pistons in the cylinder and air springs for moving the pistons on the compression stroke, in combination with a control device, means for procuring changes in the control device in response to changes in the inner end positions of the piston strokes, and means actuated by said control device for adjusting the air spring pressures, said last means including means for supplying gas to the air springs and means for controlling the rate at which gas is supplied to the air spring.

2. A free-piston unit having an engine cylinder, opposed pistons in the cylinder and air springs for moving the pistons on the compression stroke, in combination with a control device, means for procuring changes in the control device in response to changes in the inner end positions of the piston strokes, means actuated by 25 said control device for adjusting the air spring

pressures, said last means including means for supplying gas to the air springs and means for controlling the rate at which gas is supplied to the air spring, said control device also being responsive to changes in the engine exhaust pressure.

KENNETH C. COOPER.
